HERMANN ERNST RICHTER, OF TUCKAHOE, NEW YORK, ASSIGNOR TO CHARLES F. CASSENS, OF YONKERS, NEW YORK.

CRANK-SHAFT.

1,282,631.

Specification of Letters Patent. Patented Oct. 22, 1918.

Application filed November 8, 1916. Serial No. 130,295.

To all whom it may concern:

Be it known that I, HERMANN ERNST RICHTER, a subject of the Emperor of Germany, and resident of Tuckahoe, in the 5 county of Westchester, State of New York, have invented certain new and useful Improvements in Crank-Shafts, of which the following is a specification.

The device, the subject of this invention, 10 is a balanced crank shaft and its objects are to provide a shaft having means for balancing against the weight of the crank pin.

My shaft may be constructed for duplex multi-cylinder engines or single cylinder engines, and as the balancing means consists 15 of a disk or a plurality of disks the ordinary fly wheel may, under some conditions, be omitted. I do not however anticipate the omission of the fly wheel, nor do I feel that 20 this is the greatest advantage to be gained from the use of my device. I do however provide a crank shaft having no projections and one that may be balanced without difficulty.

25 The construction of my device will be set forth as the specification progresses.

The following is what I consider a good means of carrying out this invention and the accompanying drawings should be considered 30 for a complete understanding of the specification which follows:

In the drawings—

Figure 1 shows a complete crank shaft for a multi-cylinder engine.

35 Fig. 2 shows in elevation an unbalanced disk.

Fig. 3 shows a balancing disk.

Fig. 4 shows in section a disk 11.

40 Fig. 5 shows in section one of the balanced disks.

Similar reference numerals indicate like parts in all of the figures where they appear.

45 My crank shaft is provided with a plurality of bearing or supporting members, the number of which will be determined by the length of the shaft and the number of cylinders in the engine. In Fig. 1 I have shown end bearing members 1 and 2 and an intermediate bearing member 3.

50 Secured to the end of the bearing member 1 is a disk 4, the periphery of which is smooth, but it will be noted that upon one face of the disk 4 I provide a projection 5, which extends over a portion of the periphery of the disk. This projection is directly

opposite a perforation into which I introduce the first crank pin 7.

It will be noted that the bearing member 1 is introduced into a central perforation 8 in the disk 4, and that the part of the bearing member which is received in the perforation 8 is not round like a cylinder but that the portion of the end is cut away and I also call attention to the fact that each crank pin has a portion cut away at each end and that the perforations or holes into which the bearing members and the crank pins are to be introduced are not completely circular but are rather provided with a straight side as shown at 9 and 10.

70 On the free end of the member 7 I place a disk 11. It need not be a balanced disk but may be a flat completely circular disk of sufficient weight, size and thickness.

The perforations or holes through this 75 disk shown at 12 and 13 are also provided with a straight side 14 and 15.

In the hole 13 which is directly opposite the hole 12 I introduce the second crank pin 16, and upon this crank pin I place another 80 balanced disk 17 which will receive the central bearing member 3 and as each of the balanced disks are of similar construction and each of the unbalanced disks are of similar construction I need not enter into the 85 details of the construction each time that I refer to one of these members, it being sufficient to say that the balanced disks 4, 17, 19 and 23 are not unlike each other, and that the unbalanced disks 11 and 21 are very similar 90 to each other in construction, shape and size.

In the central perforation of the disk 17 I introduce the bearing member 3 and upon the other end of this member I place another 95 balanced disk 19, having a crank pin 20 introduced in its outermost perforation. An unbalanced disk 21 is arranged upon the crank pin 20 and a second crank pin 22 is engaged in the unfilled perforation in the 100 disk 21. The forth balanced disk 23 secured to the crank pin 22 and receiving the outermost bearing member 2 completes the series as shown, and when assembled as described 105 and when the parts are mechanically secured together the result will be a crank shaft which will rotate in a circle and be found to be balanced for all ordinary purposes.

When assembled as described should it be desired to more accurately balance the com- 110

pleted crank shaft a small portion of one of the projections 15 may be removed or I may remove a slight portion of the balancing disks directly opposite the projection 15, as

5 I provide in every instance a sufficient quantity of metal so that the small necessary parts may be removed without the sacrifice of strength.

In assembling my device I prefer the parts 10 should be shrunk together, but for greater security the pin 24 or key 25 may be introduced in the manner well understood.

As before stated the length of the shaft may be changed at will and my device allows 15 such a change more readily than crank shafts cast as integral units for the reason that as it is a built up shaft only the necessary number of parts need to be employed to complete a shaft of any length.

20 Modifications may be made within the scope of the appended claim, but I desire to adhere to the number of disks having con-

tinuous peripheries and inward projections by means of which a balance is secured.

Having carefully and fully described my 25 invention what I claim is—

A crank shaft comprising a plurality of disks arranged in pairs, each said disk provided with a central perforation and a perforation away from the center, and an enlarged portion formed integral with and projecting from one face and remote from the center of each said disk, a flat disk between the disks of each pair, said flat disk being provided with perforations, away 30 from the center thereof, and crank pins and shaft members secured in said disks.

Signed at New York city, county and State of New York, this 27 day of Oct., 1916.

HERMANN ERNST RICHTER.
